UNITED STATES PATENT OFFICE.

RUDOLF E. HELLMUND, OF SWISSVALE, PENNSYLVANIA, ASSIGNOR TO WESTINGHOUSE ELECTRIC & MANUFACTURING COMPANY, A CORPORATION OF PENNSYLVANIA.

RELAY.

1,871,560.

Specification of Letters Patent. Patented Mar. 15, 1921.

Application filed September 28, 1917. Serial No. 193,694.

To all whom it may concern:

Be it known that I, RUDOLF E. HELLMUND, subject of the Emperor of Germany, and a resident of Swissvale, in the county of 5 Allegheny and State of Pennsylvania, have invented a new and useful Improvement in Relays, of which the following is a specification.

My invention relates to relays and particularly to low-voltage tripping devices for 10 polyphase motor circuits.

One object of my invention is to provide means for insuring the deenergization of a 15 low-voltage holding coil when no current traverses one or more phases of the circuit.

Another object of my invention is to provide two parallel-connected switches for so controlling the circuit of a low-voltage holding coil that it will be positively deenergized upon a failure of voltage on any of 20 the phases of the circuit.

A further object of my invention is to provide a device of the above indicated character that shall be simple and inexpensive to construct and effective in its operation.

In the accompanying drawings, Figure 1 is a diagrammatic view of an electrical circuit embodying my invention; Fig. 2 is a 30 detail front elevational view of the torque motor shown in Fig. 1; Fig. 3 is a detail front elevational view of a modified form of the torque motor shown in Fig. 1, and Fig. 4 is a view taken along the line IV—IV of 35 Fig. 3.

A polyphase induction motor 1 is supplied with current through conductors 2, 3 and 4 of an electrical circuit. A circuit interrupter 5 and a switch 6 are connected in series 40 with the conductors 2, 3 and 4, and the circuit interrupter 5 is provided with a no-voltage or low-voltage holding coil 7 for the purpose of opening the interrupter 5 when the voltage fails on one or more phases 45 of the circuit supplying energy to the motor 1.

One terminal of the holding coil 7 is connected to the conductor 4 and its other terminal is connected to the contact member 50 8 of a switch 9 and to the contact member 10 of a switch 11. The switch 9 comprises a movable bridging contact member 12 and two resiliently mounted contact members 8 and 13. The movable bridging contact 55 member 9 is so mounted on the movable

member of the switch 6 that it engages the resiliently mounted contact members 8 and 13 when the switch 6 is opened. Two stationary members 14 are provided for so engaging the contact members 8 and 13 that, 60 when the bridging contact member 12 is moved downwardly, it will disengage the same after it has moved a predetermined distance. The contact member 13 is connected to the conductor 3 of the circuit and 65 to the stationary contact member 15 of the switch 11.

The switch 11 comprises the stationary contact members 10 and 15, a movable bridging contact member 16, a spring 17 for 70 biasing the member 16 to its open position and a torque motor 18 for moving the same to its closed position. The motor 18 is operatively connected to series transformers 19 that are associated with the conductors 2, 75 3 and 4 of the circuit. The motor 18 may be constructed along the lines of an induction motor and it is adapted to maintain the contact member 16 in engagement with its stationary contact members 10 and 15 when 80 current traverses conductors 2, 3 and 4. However, when no current traverses one or more of the phases, the motor 18 will act as a single-phase motor, and, since its rotor is stationary, it will lose its torque and permit the spring 17 to open the switch 11.

When the circuit interrupter 5 is closed, and low voltage obtains across the conductors 3 and 4, the holding coil 7 will be overcome by a spring 26 to permit the interrupter 5 to be opened. However, when the switch 6 is closed, the circuit through the trip coil 7 is opened at the switch 9, but, if current traverses all of the conductors 2, 3 and 4 of the circuit, the motor 18 will immediately close the switch 11. Thus, when one of the conductors 2, 3 and 4 is interrupted, the switch 11 will open to deenergize the holding coil 7 and permit the spring 26 to open the interrupter 5.

My invention is particularly adaptable to polyphase induction-motor circuits in which the converter action of the induction motor maintains voltage across all of its phases even when the current traversing 105 one the phases is interrupted. In other words, it is adapted to prevent the failure of operation of the low-voltage coil when voltage is induced in the circuit by the motor.

If it is desired to connect the motor 18 110

directly in circuit with the conductors 2, 3 and 4 without the use of the transformers 19, it may be constructed as shown in Fig. 2, in which the conductors 2, 3 and 4 constitute the windings of the stator 24 and in which the rotor 20 is constructed in accordance with the usual construction of squirrel-cage rotors. That is, the conductors 2, 3 and 4 of the circuit pass directly through the 10 stator and are so displaced with respect to each other that they coöperate with the squirrel-cage rotor 20 to develop torque.

In Figs. 3 and 4 of the drawings, the motor 18 may comprise a stator 25 having three 15 castings 21, 22 and 23 constituting the windings. The castings 21, 22 and 23 are of such shape that they form the windings and the terminals of the conductors 2, 3 and 4. That is, the castings are adapted to be received 20 in properly displaced openings in the stator of the motor to constitute conductors and end connections therefor and also terminals to which the line conductors may be directly connected to thus preclude the use of the 25 transformers 19. An ordinary squirrel-cage rotor may be used.

I do not limit my invention to the particular structures illustrated, as various modifications may be made without departing 30 from the spirit and scope of the invention as set forth in the appended claims.

I claim as my invention:

1. In a polyphase electric circuit, the combination with a switch, a circuit interrupter, 35 and a low-voltage coil therefor, of means dependent upon the closure of the switch for opening the circuit of the coil, and means for closing the circuit of the coil when current traverses each phase of the circuit.

40 2. In a polyphase electric circuit, the combination with a switch, a circuit interrupter and a low-voltage coil therefor, of two parallel-connected switches for the low-voltage coil circuit, and means for causing one of 45 the switches to be automatically opened when the current traversing one of the phases of the circuit is interrupted.

3. In a polyphase electric circuit, the combination with a main switch, a circuit interrupter and a low-voltage holding coil therefor, of two parallel-connected switches for the circuit of the holding coil, means for opening one of the switches when the main switch is closed and means for closing the 55 other switch only when current traverses all phases of the circuit.

4. In a polyphase electric circuit, the combination with means for closing the circuit, and a low-voltage coil for effecting opening 60 of the circuit, of two parallel-connected

auxiliary switches for the low-voltage coil, means for opening one of the switches when the main circuit is closed, and means for closing the other switch only when current traverses all phases of the electric circuit. 65

5. In an electric circuit, the combination with means for closing the circuit and a low-voltage holding coil for controlling the opening of the circuit, of means dependent upon the closing of the circuit for disconnecting the holding coil from the circuit, and means for connecting the holding coil to the circuit only when current traverses the same. 70

6. In a polyphase electric circuit, the combination with means for closing the circuit and a holding coil controlling the opening of the circuit, of means dependent upon the closing of the circuit for disconnecting the holding coil from the circuit, and an induction motor for maintaining the circuit of the holding coil closed only when current traverses all phases of the circuit. 75

7. In an electric circuit, the combination with means for closing the circuit and a holding coil for controlling the opening of the circuit, of means dependent upon the closing of the circuit for disconnecting the holding coil, and means for connecting the holding coil only when current traverses 90 the circuit. 85

8. In an electric circuit, the combination with a main switch, a circuit interrupter and a low-voltage holding coil therefor, of two parallel-connected switches for the circuit of the holding coil, and means for opening one of said switches when the main switch is closed. 95

9. In a polyphase electric circuit, the combination with a main switch, a circuit interrupter and a low-voltage holding coil therefor, of an auxiliary switch actuated by the main switch for opening the circuit of the holding coil when the main switch is closed, a second auxiliary switch in the circuit of the holding coil, and a current relay for opening the second auxiliary switch when no current traverses one phase of the circuit. 100

10. In a polyphase electric circuit, the combination with a circuit interrupter and a low-voltage holding coil therefor, of two parallel-connected switches for the circuit of the holding coil, and an induction motor for closing one of said switches when current traverses all phases of the circuit. 110

In testimony whereof, I have hereunto subscribed my name this 11th day of Sept., 1917.

RUDOLF E. HELLMUND.
